Primary Examiner — Sandra S Snapp*Assistant Examiner* — Katherine Glennon(74) *Attorney, Agent, or Firm* — McDonnell Boehnen Hulbert & Berghoff LLP(57) **CLAIM**

The ornamental design for a timer, as shown and described.

DESCRIPTION

FIG. 1 is an embodiment of a timer in a perspective view; FIG. 2 is a front view thereof;

FIG. 3 is a rear view thereof;

FIG. 4 is a left side view thereof;

FIG. 5 is a right side view thereof;

FIG. 6 is a top view thereof; and,

FIG. 7 is a bottom view thereof.

The broken lines illustrate portions of the timer that form no part of the claimed design.
